UNITED STATES PATENT OFFICE

JAMES THOMAS JOHNSON, OF NASHVILLE, TENNESSEE, ASSIGNOR OF ONE-HALF TO
EDWIN F. BOBBITT, OF NASHVILLE, TENNESSEE

WINDOW SCREEN

Application filed November 26, 1927. Serial No. 235,867.

This invention relates to an improved window screen structure, and it has particular reference to a structure of this class, wherein the screen is constructed for swinging movement in the window frame.

More particularly, the invention has reference to a so-called half-screen which is constructed and mounted in such a way as to permit it to occupy either a lower position, or an upper position, thus making it permissible to move the screen from the lower half of the window frame, at night, up to the top half, and permitting the upper sash to be lowered and the window blinds raised to promote free ventilation.

The particular construction and other advantages of the invention will become more readily apparent from the following description and drawings.

20 In the drawings:—

Figure 1 is an outside elevational view of a window frame showing the improved screen located in the upper half of the window frame above the hingedly mounted shutters.

25 Fig. 2 is an inside view, of certain of the features shown in section, with the other features removed for clearness, taken on the line 2—2 of Fig. 4.

Fig. 3 is a horizontal section taken approximately upon the plane of the line 3—3 of Fig. 1.

Fig. 4 is a vertical section on the line 4—4 of Fig. 1.

Fig. 5 is a view like Fig. 4, showing the screen down and ready to be positioned in the lower portion of the window frame.

Fig. 6 detail view of one of the extensible retaining links forming an important part of the invention.

40 Referring now to the drawings in detail, and particularly to Figs. 4 and 5, it will be seen that the reference character 7 designates generally a window frame in which slideable sashes are mounted in the customary manner.

45 The upper sash is designated by the numeral 7 and the lower one by the numeral 9. The screen, which is of the half-type, is generally designated at 10 and the swingable hingedly mounted shutters by the numerals 11.

50 The shutters as shown in Fig. 1, preferably

occupy the lower half of the window frame. I also wish to call attention to the cross strips providing a stop and carrying a small eye-bolt 13. I also call attention to a small eye bolt 14 in the window frame just above the 55 lower rail of the upper sash. The window screen comprises a frame 15, whose vertical side bars are formed with grooves along the marginal edges as indicated better in Fig. 3.

Fastened on the frame is a customary wire 60 mesh-screen 16 held in place by molding 17. There is a small hook 18 carried by the top rail of the screen frame, this being adapted for connection with the eye bolt 13. In addition, there are hooks 19 fastened to the vertical side rails of the screen frame, these being intended to be detachably connected with the eye bolt 14.

I employ a pair of duplicate retaining links, these being generally designated by the 70 numerals 20 and each including a tube 21 in which a rod 22 is slideable. The tube is flattened at its upper end and pivotally connected to the window frame as at 23, and the rod is pivotally connected in the grooved side bars 75 of the screen frame.

Adjustment between the rod and screw members is maintained through the use of the set screw 24. It is obvious that the screen and links may occupy either the position 80 shown in Figs. 4 or the position shown in Fig. 5.

In either position, the screen bears against the cross piece 12. When in the lower position, shown in Fig. 5, the screen is of course 85 swung completely into the window frame, and is hooked in place by the hook 18 which is then engaged with the small eye-bolt 13. When in the raised or elevated position shown in Fig. 4, it is held in place by the hooks 19 90 which are engaged in the eyes 14. In either position, it is held partly by the extensible links. In addition, the links constitute the means for facilitating the movement of the screen from one position to another.

95 From the foregoing, it will be seen that I have evolved and produced a half screen which can be used either at the top or bottom, thereby taking the place of a whole screen. The screen can be set at any angle, 100

when washing windows and when dusting screens to prevent the dust from being on the inside of the house.

When the screen is at bottom, remove the hook 18, and push the top out. This automatically unlocks the screen so that it can then be swung up. This screen has the advantage of the old style screen being held in place both at the top, center, and bottom.

10 When the screen is at the bottom, it is held in place at the top end by hooks, in the center by the invisible hanger and hinged links, and at the bottom by the small dowel pins fitting into small sockets.

15 The screen is thus prevented from warping. The screen does not interfere with the use of half shutters, as the screen is never in the way of the shutters. When the shutters are closed, the screen is at the top. The links 20 are adjustable permitting the screen to be used in different types of window frames.

Having thus described my invention, what I claim as new is:—

In combination with a half screen embodying a frame including a top, bottom and side pieces, and having one of said side pieces formed along its outer marginal edge and on its inner side with a groove, a retention and attaching link connected to said last mentioned side member and foldable into said groove, and said link embodying a tube apertured and flattened at its outer end, and a rod telescoping into said tube, together with a set screw carried by said tube and engageable with the rod.

In testimony whereof I affix my signature.

JAMES THOMAS JOHNSON.
